CLAIM

The ornamental design for a note pad wallet or the like, substantially as shown and described.

DESCRIPTION

FIG. 1 is a front perspective view of a note pad wallet showing my new design;

FIG. 2 is a front elevational view thereof;

FIG. 3 is a top plan view thereof;

FIG. 4 is a left side elevational view thereof, the right side being a substantial mirror image thereof;

FIG. 5 is a rear elevational view thereof;

FIG. 6 is a bottom plan view thereof;

FIG. 7 is a left side elevational view thereof with the wallet shown folded over in a closed position;

FIG. 8 is a front perspective view of a modified form of the note pad wallet showing my new design wherein hook and loop fastener strips are located near the upper and lower ends of the front surface;

FIG. 9 is a front elevational view thereof, the rear elevational view being shown in FIG. 5;

FIG. 10 is a top plan view thereof;

FIG. 11 is a left side elevational view thereof, the right side being a substantial mirror image thereof;

FIG. 12 is a bottom plan view thereof; and

FIG. 13 is a left side elevational view thereof with the wallet shown folded over in a closed position.

Note pads are shown in broken lines in FIGS. 7 and 13 for illustrative purposes only, and do not form part of the claimed design.
